(57) **CLAIM**

The ornamental design for a medical device, as shown and described.

DESCRIPTION

FIG. 1 is a front perspective view of a medical device showing the new design;

FIG. 2 is front elevation view of the medical device;

FIG. 3 is a rear elevation view of the medical device;

FIG. 4 is a left elevation view of the medical device;

FIG. 5 is a right elevation view of the medical device;

FIG. 6 is a top view of the medical device;

FIG. 7 is a bottom view of the medical device;

FIG. 8 is a rear perspective view of the medical device;

FIG. 9 is another front perspective view of the medical device, showing additional environmental structure;

FIG. 10 is an enlarged portion of FIG. 12;

FIG. 11 is an enlarged portion of FIG. 13;

FIG. 12 is a top perspective view of the medical device; and,

FIG. 13 is a bottom perspective view of the medical device. The broken lines in FIGS. 1-13 illustrate portions of the medical device that form no part of the claimed design.

The dash-dot lines in FIGS. 10 and 12 indicate the boundary of the enlarged portion of FIG. 12 and form no part of the claimed design.

The dash-dot lines in FIGS. 11 and 13 indicate the boundary of the enlarged portion of FIG. 13 and form no part of the claimed design.

1 Claim, 13 Drawing Sheets
